UNITED STATES PATENT OFFICE.

ALONZO D. SEAMAN, OF MILWAUKEE, WISCONSIN.

VACUUM-CLEANER FOR RUGS.

1,149,169.

Specification of Letters Patent.

Patented Aug. 3, 1915.

Application filed September 26, 1912. Serial No. 722,507.

To all whom it may concern:

Be it known that I, ALONZO D. SEAMAN, a citizen of the United States, residing at Milwaukee, in the county of Milwaukee and 5 State of Wisconsin, have invented new and useful Improvements in Vacuum-Cleaners for Rugs, of which the following is a full, clear, concise, and exact description, reference being had to the accompanying drawing, forming a part of this specification.

This invention relates to fabric cleaning machines.

It is particularly applicable to machines for cleaning rugs and heavy fabrics.

15 Machines for cleaning heavy fabrics generally employ a beater or brush for loosening and dislodging the dust and dirt. An exhaust apparatus is sometimes associated with the machine to remove the dirt after 20 it has been disengaged from the fabric. The process of cleaning a fabric by beating and brushing requires the expenditure of a relatively large amount of energy over a considerable period of time. The fabric is in 25 a cloud of dust during the operation. Some of the dust is removed by the exhaust; some of it settles back on the fabric; and the remainder is scattered about the machine and throughout the atmosphere. The problem 30 has been to devise a machine which will thoroughly clean a fabric in the shortest possible period of time with the expenditure of a minimum amount of energy and without scattering the dust and dirt 35 throughout the atmosphere of the room. To this end the present invention has been devised.

An object of the present invention is to provide an improved machine for thoroughly and quickly cleaning a fabric.

Another object is to provide a simplified machine in which the dust and dirt is positively removed from a fabric with the expenditure of a minimum amount of time and 45 energy.

Another object is to provide an improved machine in which a fabric may be thoroughly cleaned without scattering the dust and dirt throughout the atmosphere about 50 the machine.

Other objects and advantages of the invention will hereinafter appear.

In its preferred form the machine is provided with a suction bed over which the 55 fabric is passed. The fabric is held spaced from this bed adjacent the nozzle or port of

the suction device, so as to extend the zone of suction. The beater operates on this suction zone, and a suction is applied simultaneously which is sufficiently strong to withdraw dust and dirt from the fabric and also to remove all the material loosened by the beater. The rug is thereby thoroughly cleaned with the expenditure of a minimum amount of energy.

One embodiment of the invention is illustrated in the accompanying drawings, in which—

Figure 1 is a side elevation; Fig. 2 is a vertical section; Fig. 3 is a plan view of a 70 table and suction bed; Fig. 4 illustrates details of the driving mechanism.

The cleaning machine is provided with a frame 1. The frame supports a table 2, a draw-roll 3, a beater 4, a suction bed 5 and 75 a vacuum chamber 6. The frame which supports the various parts of the machine has two legs 7 at each end, connected by bars 8. The draw-roll 3 is supported in suitable bearings 9, carried by brackets 10, 80 projecting forwardly from the ends of the frame. A rod 11, on the draw-roll, provides suitable means to which the end of the fabric may be attached. The beater roll is journaled in upright supports 12, rising from 85 the top of the frame and is provided with lashes or thongs 13 of leather or other material suitable to deliver a succession of sharp blows to the fabric upon rotation of the roll.

The suction bed communicates with the 90 vacuum chamber 6 through a suitable port herein shown as an elongated slot 14. The upper surface 15 of the bed is suitably channeled or corrugated for a purpose herein-after described. The channels may be 95 formed in various ways. In the preferred form parallel cleats 16 extend across the bed surface to form channels. These cleats preferably overhang the port 14 at 17 to prevent the fabric being drawn too tightly 100 against the port and sealing the same. Pipes or conduits 18 connect the chamber 6 with a suitable exhaust fan or pump, not shown.

Any suitable means may be provided for 105 driving the machine. The means selected for illustration comprises a small electric motor 19 supported on a bed plate 20 pivoted to swing on a supporting bracket 21. The motor shaft 22 carries a pair of friction surfaces 23 and 24 adapted to cooperate respectively with friction disks 25

and 26 carried by a shaft 27. The shaft 27 drives the draw-roll 3 through a reversible worm and gear 29.

The beater roll is driven by a belt 31 passing over a pulley 30 on the motor shaft and a pulley 32 on the beater roll. An idle pulley 33, adjacent the belt, is adapted to be shifted against the belt to tension the same. A reversing lever 34 is connected to 10 the motor bed, and, by shifting the bed about its pivot, either friction surface may be brought into contact with its disk to drive the draw-roll, to wind the rug thereon, or to unwind the same.

15 The operation of the cleaner is substantially as follows: One end of the rug or fabric to be cleaned is attached to the draw-roll. Upon starting the mechanism, the draw-roll will slowly draw the rug between 20 the beater and the suction bed. The arrangement of parts is such that a strong suction is exerted over a considerable portion of the fabric with the expenditure of a minimum amount of energy. The zone of action 25 of the suction device is extended and the beater operates upon the fabric as it is being passed through this extended zone. The beater loosens the dirt and dust, while the suction draws the dirt from the rug 30 and carries it away without permitting its escape into the atmosphere.

The cleats of the suction bed may, of course, assume various forms which will hold the rug spaced from the bed to permit 35 action of the suction on the entire portion of the fabric which is beaten. By reversing the controlling lever the draw-roll may be reversed to unwind the rug therefrom.

What I claim as new and desire to secure 40 by Letters Patent of the United States is:

1. A fabric cleaning machine comprising a frame, a suction bed supported thereby over which the fabric is passed, said bed being provided with channels in its upper surface extending substantially parallel to the direction of movement of the fabric, a beater adapted to beat the fabric as it passes over the channeled portion of the bed, said bed having a suction port therein extending 45 transversely to the channels and communicating therewith whereby a suction may be produced on the fabric as it passes over the channels and the port to remove the dust and dirt from said fabric.

50 2. A fabric cleaning machine comprising

a suction bed over which the fabric is passed having a plurality of spaced ribs on its surface extending substantially parallel to the direction of movement of the fabric whereby a plurality of channels are formed on the 60 surface of the bed, a beater adapted to beat the fabric as it passes over the channeled portion of the bed, said bed being provided with a suction port extending transversely to the channels and communicating therewith whereby a suction may be produced on the fabric as it passes over the channels and the port to positively remove the dust and dirt therefrom, said ribs extending over 65 said port whereby the fabric is prevented 70 from sealing the port.

3. A fabric cleaning machine provided with a surface over which the fabric is passed having a relatively narrow suction port therein extending transversely to the 75 direction of movement of the fabric, said surface having a plurality of channels therein communicating with the suction port and means for beating the fabric as it passes over said channeled surface.

4. A fabric cleaning machine provided with a suction bed over which the fabric is passed having a suction port therein extending transversely to the direction of movement of the fabric, said bed being provided 85 with channels in its upper surface extending substantially parallel to the direction of movement of the fabric and communicating with the suction port for extending the zone of action of the suction through said port 90 and a means for beating the section of fabric passing through said zone.

5. A machine for cleaning fabrics provided with a bed over which the fabric is passed having a relatively narrow suction 95 port therein extending transversely to the direction of movement of the fabric, a plurality of ribs on the surface of said bed having spaces therebetween communicating with said port whereby the fabric is prevented from sealing said port, and means 100 for beating the section of fabric passing over the ribbed portion of the bed.

In witness whereof, I have hereunto subscribed my name in the presence of two witnesses.

ALONZO D. SEAMAN.
